UNITED STATES PATENT OFFICE.

WILLIAM HENRY FESLER, OF COLUMBIANA, OHIO.

MUSIC-LEAF TURNER.

SPECIFICATION forming part of Letters Patent No. 352,310, dated November 9, 1886.

Application filed July 24, 1886. Serial No. 209,020. (No model.)

To all whom it may concern:

Be it known that I, WILLIAM HENRY FESLER, of Columbiana, in the county of Columbiana and State of Ohio, have invented a new and Improved Music-Leaf Turner, of which the following is a specification, reference being had to the annexed drawings, forming a part thereof, in which—

Figure 1 is a front elevation of my improved leaf-turner. Fig. 2 is a vertical transverse section taken on line $x x$ in Fig. 1. Fig. 3 is an inverted plan view with the bottom removed, and Fig. 4 shows the application of the sheet-turner.

Similar letters of reference indicate corresponding parts in the different figures of the drawings.

The object of my invention is to provide a simple and efficient device for quickly turning the leaves of music or music-books, or for turning single sheets of music.

My invention consists in the construction and arrangement of parts, as will be herein-after fully described and claimed.

The base A is made of two parts, $a b$, the part a being recessed to form a chamber, c. In the base is journaled a vertical rock-shaft, D, upon which and within the chamber c is placed a pinion, e. In the chamber c is pivoted a lever, E, carrying on its inner and shorter end the toothed sector f, and at its outer end the finger-piece g. The toothed sector f engages the pinion e, so that when the lever E is swung on its pivot the shaft D will be turned. The upper end of the rock-shaft D is squared, to receive a socket, D', and in the upper end of the said socket is inserted a pair of wires, $h h'$, which extend upward parallel with each other for about half their length, and are then bent outward at right angles with the axis of the socket.

Behind the rock-shaft D, and at one side thereof, a square stud, B, is inserted in the base A, and to the stud B is fitted a socket, B', carrying at its upper end a cross-bar, C, upon the ends of which are secured wire forks d, which extend upward and receive between their arms a sheet of music.

When the instrument is to be used in connection with a book, the socket B' is removed,

and the leaf of the book to be turned is received between the wires $h h'$, and the turning is effected by swinging the key-lever E in one direction or the other, according to the requirements.

When a sheet of music is to be turned so as to show oppositesides, the socket D' is removed from the rock-shaft D and replaced by the socket B', which carries between its forks d the sheet of music. If desirable, the socket B' may remain upon the stud B, and may be used for holding a sheet of music which does not require turning, and a leaf may be inserted between the wires $h h'$ and turned in front of the sheet supported by the forks d.

Having thus described my invention, what I claim as new, and desire to secure by Letters Patent, is—

1. In a music-leaf turner, the combination, with the base-piece having a chamber, a vertical rock-shaft projecting through the top of the base, a pinion on said shaft within the chamber, and a pivoted finger-piece having a toothed segment on its inner end engaging the said pinion, of the removable socket on the outer end of the rock-shaft and parallel angle-wires on said socket, substantially as set forth.

2. A music-leaf turner and holder comprising a vertical rock-shaft and its operating finger-piece, the removable socket on the upper end of the said shaft, the angle-wires projecting from said socket, the post, the vertical removable socket thereon, the transverse bar at the upper end thereof, and holding-arms at opposite ends of said bar, substantially as set forth.

3. In a music-leaf turner, the combination of the base-piece A, provided with the chamber c, the rock-shaft D, the pinion e, carried thereby, the socket D', fitted to the rock-shaft, and parallel angled wires $h h'$, carried thereby, the key-lever E, provided with the toothed sector f and finger-piece g, and the sheet-music holder formed of the socket B', the cross-bar C, and wire forks d, substantially as shown and described.

WILLIAM HENRY FESLER.
